(57) **CLAIM**

The ornamental design for a dog toy box, as shown and described.

DESCRIPTION

FIG. 1 is a perspective view of a dog toy box with the lid in a closed position;

FIG. 2 is a front elevational view thereof;

FIG. 3 is a rear elevational view thereof;

FIG. 4 is a top plan view thereof;

FIG. 5 is a right side elevational view thereof, the left side elevational view being a mirror image thereof; and,

FIG. 6 is a perspective view of the dog toy box shown in FIG. 1 with the lid in an open position.

The dashed lines shown in the drawings represent stitching and form part of the claimed design. The cross-hatching indicates a leather-like surface treatment that extends across the entirety of the surfaces on which it is shown.
